UNITED STATES PATENT OFFICE.

EDWIN F. MERSICK, OF NEW HAVEN, CONNECTICUT, ASSIGNOR TO ENGLISH
& MERSICK.

SPEAKING-TUBE.

SPECIFICATION forming part of Letters Patent No. 434,672, dated August 19, 1890.

Application filed May 19, 1890. Serial No. 352,387. (No model.)

To all whom it may concern:

Be it known that I, EDWIN F. MERSICK, of New Haven, in the county of New Haven and State of Connecticut, have invented a new Improvement in Speaking-Tubes; and I do hereby declare the following, when taken in connection with accompanying drawings and the letters of reference marked thereon, to be a full, clear, and exact description of the same, and which said drawings constitute part of this specification, and represent, in—

Figure 1, a side view of the tube with the mouth-piece attached; Fig. 2, a longitudinal section through one of the mouth-pieces and a portion of the tube; Fig. 3, a longitudinal section of the mouth-piece detached, and Fig. 4 the divided spring-ring detached.

This invention relates to an improvement in speaking-tubes such as used upon carriages as a communication from the occupants to the coachman, and in which the tube is flexible, applicable also to other purposes, the object of the invention being, first, to construct the mouth-piece with the whistle stationary therein, and also to unite the flexible tube with the mouth-piece in a simple and durable manner; and the invention consists in the construction as hereinafter described, and particularly recited in the claims.

30 A represents the mouth-piece which is intended for use at the coachman's end of the tube, and B the mouth-piece which is intended for the inside end of the tube, C being the flexible tube connecting the two mouth-pieces.

35 The flexible tube is constructed from wire spirally wound and covered with fabric. In Fig. 2 this tube is shown in longitudinal section. The mouth-pieces are made from wood, hard rubber, or other suitable material, and are constructed with a socket C at the tube end. This socket is of an internal diameter

40 corresponding to the external diameter of the spiral-wire portion of the tube, and is internally grooved with a spiral groove corresponding to the spiral wire of the tube, and so as to form practically an internal screw-thread in the socket, as seen in Fig. 3, which corresponds to the spiral surface of the tube, and so that the tube may be screwed into the 45 socket, the convolutions of the wire operating

as a screw-thread to draw the tube into the socket. That the fabric covering may be inclosed and protected at that end, the socket is constructed at that end with a recess so much larger than the wire part of the tube as 55 to extend over the covering, as seen in Fig. 2. This forms a recess a in the end of the socket, which incloses the covering of the tube, so as to protect and give a finish to the covering at its junction with the mouth-piece, it 60 being understood that the covering is removed on that portion of the tube which enters the screw-threaded portion of the mouth-piece. This union between the mouth-piece and tube makes a firm connection, which is not 65 liable to be accidentally detached, but yet permits the mouth-piece to be readily removed should occasion require.

The whistle is placed inside the mouth-piece. To permanently unite the whistle with 70 the mouth-piece, and so that it may be stationary therein, the mouth-piece is constructed with an annular shoulder b on its inside distant from the outer end of the mouth-piece so far as to be out of the way of the lips. 75 Against this shoulder the whistle D is set, the whistle being a common mouth-piece whistle, and around the interior of the mouth-piece outside the whistle an annular groove d is formed, into which a divided wire ring e 80 is placed. This wire ring is represented in Fig. 5 detached. It is made from wire of a diameter somewhat greater than the diameter in the groove d, and a portion of the ring is cut away, as at f. The ring is elastic, 85 so that it may be pressed into the mouth-piece, contracting until it reaches the groove d, when it will expand into the groove and there lie against the whistle, so as to secure the whistle between the shoulder d and the 90 said divided ring, thus firmly holding the mouth-piece in place.

The opening through the whistle is sufficient for speaking purposes without disturbing the position of the whistle, and the call 95 is made from the other mouth-piece by blowing, as usual in speaking-tubes where whistles are employed as the signal.

Both mouth-pieces may be provided with a whistle, if desired; but in case of a carriage- 100

tube the one at the coachman's end is all that is necessary.

I claim—

1. In a speaking-tube in which the tube is made from a spiral-wire body, the combination therewith of a mouth-piece constructed with a socket at the tube end, the socket internally screw-threaded corresponding to the convolutions of the wire body, the end of the wire body screwed into the said socket, the convolutions of the wire forming the screw-thread for the union of the mouth-piece and tube, substantially as described.

2. In a speaking-tube, the mouth-piece constructed with an internal shoulder *b* and with an annular groove *d* outside said shoulder, a whistle *D*, set against said shoulder, and the divided spring-ring *e* in said groove *d*, substantially as described, and whereby the said whistle is secured in the mouth-piece between the said shoulder and the said ring. 15 20
